CONDENSER PLIERS

Earl E. Mitchell, P.O. Box 10006, Fort Worth, Tex.
Filed Mar. 2, 1964, Ser. No. 348,484
2 Claims. (Cl. 29—203)

This invention relates to pliers which are designed especially for convenience in attaching lead wires to an electric condenser of a type which is commonly employed as a capacitor for the ignition of a small gasoline engine, while the condenser is in place in the engine housing.

The pliers of the invention are peculiarly adapted for use in conjunction with a cylindrical electric condenser which is characterized by its small size, whereby it is difficult to handle manually, and which has a binding post aligned with its longitudinal axis and extending longitudinally outwardly from one of its ends, said binding post having a hole extending transversely through it near its outer end for engagement by a pair of lead wires, and a compression spring surrounding said binding post, and confined between said hole and the adjacent end of the condenser when fully compressed, for frictional yieldable engagement with said wires and the adjacent end of the condenser to prevent displacement of said wires from said binding post.

A condenser as described may be no more than about 1½ inches long and about ½ of an inch in diameter, for example, and the binding post and the compression spring may be several times smaller than the condenser, so that it is difficult to depress the spring while at the same time threading the two lead wires through the small hole in the binding post, particularly in locations where space is limited. The spring often is catapulted into the air and lost, and for that reason it is common practice to provide a spare spring for each condenser as it is offered for sale.

One manufacturer of such condensers provides a small annular tool formed of plastic material which is engageable over the outer end of the binding post, for temporary use in depressing the spring preparatory to inserting the ends of the lead wires in the hole of the binding post, but such tool, which weighs practically nothing and is very small itself, may be inadvertently displaced and lost along with the spring.

Pliers have heretofore been provided for use in attaching lead wires to a condenser as described, said pliers having a first jaw engageable with the end of the condenser opposite the binding post, and a second jaw having an end portion engageable with the outer end of the spring whereby the spring is depressed upon advancing said jaws relative to each other, but such pliers have handles which are substantially aligned inversely with the respective jaws so that in use the operator's hand necessarily is positioned in his line of vision and obscures the work.

An object of this invention is to provide pliers for use as described having handles which extend substantially at right angles to the respective jaws thereof so that in use the operator's hand is removed from his line of vision and the work may be observed satisfactorily at all times.

Another object of the invention is to provide pliers as described in which one of the jaws thereof has a bifurcated end portion whereby it is adapted to straddle the outer end of the binding post while at the same time depressing the spring, upon advancing the jaws relative to each other, and in which said one of the jaws has an inclined groove beginning at one side thereof and communicating with the notch between opposite sides of said bifurcated end portion for use in guiding the ends of the lead wires through the hole of the binding post in the depressed position of the spring.

2

A further object of the invention is to provide pliers as described which are formed of light gauge, narrow metal strips characterized by their resilience, and in which the handles are comparatively long relative to the lengths of the jaws. The jaws are spaced apart a variable distance, corresponding substantially to the lengths of the condenser and the compression spring together in the compressed and expanded positions, respectively, of the spring, and the handles are spaced apart a variable distance, relatively shorter than the spacing between the jaws, and abut one another in the compressed position of the spring to thereby limit movement of the jaws, upon advancing them relative to each other, whereby crushing of the condenser is prevented.

5 15 A further object of the invention is to provide pliers as described which are characterized by their simplicity and may be fabricated inexpensively, and which are attractive in their appearance, efficient in operation, and durable in use.

10 20 These and other objects will become apparent from the following description and the accompanying drawing, wherein:

FIGURE 1 is a longitudinal view showing a condenser as described in place, such as in the housing of an engine, and showing pliers embodying the invention, illustrating the manner in which the pliers are used to depress the compression spring preparatory to inserting the adjacent ends of a pair of wires in the hole of the binding post.

25 30 FIGURE 2 is an exploded perspective view on an enlarged scale showing the condenser and its binding post, the compression spring, and end portions of a pair of wires.

35 FIGURE 3 is a fragmentary perspective view on an enlarged scale showing the bifurcated end portion of one of the jaws, said jaw having an inclined groove beginning on one of its sides and communicating with the notch between opposite sides of said bifurcated end portion.

40 45 FIGURE 4 is a fragmentary longitudinal view on an enlarged scale, partly broken away to show details of construction, showing a portion of the apparatus illustrated in FIGURE 1, illustrating the manner in which said inclined groove is used to guide the adjacent ends of the lead wires through the hole of the binding post, in the compressed position of the spring.

50 55 FIGURE 5 is a view similar to FIGURE 4, showing the spring in its expanded position, in frictional, yieldable engagement with said wires, whereby said wires are prevented from being displaced from said binding post.

Referring to the exemplary form of the invention shown in the drawing, the numeral 10 designates generally an electric condenser as hereinafter described, which as shown in FIGURE 1 is employed as a capacitor for an ignition system, shown fragmentarily and indicated generally by the numeral 11, and is removably connected to the housing thereof by a bracket 12.

The condenser 10 is cylindrical and has a binding post 13 aligned with its longitudinal axis and extending longitudinally outwardly from one of its ends. The binding post 13 has a hole 14 extending transversely through it near its outer end for engagement by a pair of wires 15. A compression spring 16 surrounds the binding post 13 and is confined between the hole 14 and the adjacent end of the condenser 10 when fully compressed, for frictional, yieldable engagement with the wires 15 and the adjacent end of the condenser 10 to positively prevent displacement of the wires 15 from the binding post 13.

60 65 70 The numeral 17 generally indicates pliers embodying the invention as hereinafter described. The pliers 17 include a first elongated lever 18 and a second elongated

lever 19 which are formed of light gauge, narrow metal strips characterized by their resilience. The first and second levers 18, 19 are bent right angularly intermediate their ends to form relatively longer and shorter end portions, and are pivotally connected to each other, as at 20, at a point where the longer end portion of the second lever 19, which is longer than the corresponding end portion of the first lever 18, crosses the shorter end portion of the first lever 18, which is longer than the corresponding end portion of the second lever 19.

The pliers 17 have first and second jaws 21, 22 and first and second handles 23, 24 corresponding to portions of the first and second elongated levers 18, 19, respectively, on opposite sides of their pivotal connection 20, the handles 23, 24 being comparatively long relative to the lengths of the jaws 21, 22.

While the first handle 23 and the second jaw 22 are bent right angularly intermediate their ends, the outer end portions of the handles 23, 24, which are arranged parallel to each other in one position thereof, extend substantially at right angles to the outer end portions of the respective jaws 21, 22, which likewise are arranged parallel to each other in one position thereof.

The outer end portions of the jaws 21, 22 are spaced apart a variable distance, corresponding substantially to the lengths of the condenser 10 and the compression spring 16 together in the compressed and expanded positions, respectively, of the spring 16, and the outer end portions of the handles 23, 24 are spaced apart a variable distance, relatively shorter than the spacing between the outer end portions of the jaws 21, 22, and about one another in one position thereof to thereby limit movement of the jaws 21, 22 upon advancing them relative to each other.

As shown best in FIGURE 3, the extreme outer ends of the jaws 21, 22, or either of them, are bifurcated, as at 25, and have an inclined groove 26 therein beginning at one side thereof and communicating with the notch between opposite sides of the bifurcated end portion 25.

In operation, the outer end portion of one of the jaws 21 is engageable with the end of the condenser 10 opposite its binding post 13, and the bifurcated end portion 25 of the other of the jaws 22 is caused to straddle the outer end of the binding post 13, while at the same time depressing the spring 16 upon squeezing the handles 23, 24 together. The inclined groove 26 provides a passage between said other of the jaws 21, 22 and the adjacent end of the spring 16 for use in guiding the adjacent ends of the wires 15 into the hole 14 of the binding post 13. Crushing of the condenser 10 is positively prevented by abutment of the outer ends of the handles 23, 24 against each other, to thereby limit relative movement of the jaws 21, 22, as above described, and by the inherent resilience of the elongated levers 18, 19 and the lengths of the handles 23, 24 relative to the lengths of the jaws 21, 22.

The invention is not limited to the exemplary construction herein shown and described, but may be varied within the scope of the appended claims.

What is claimed is:

1. In pliers for use in attaching lead wires to a cylind-

rical electric condenser which is characterized by its small size, and which has a binding post aligned with its longitudinal axis and extending longitudinally outwardly from one of its ends, said binding post having a hole extending transversely through it near its outer end for engagement by said lead wires, and a compression spring surrounding said binding post, and confined between said hole and the adjacent end of the condenser when fully compressed, for frictional, yieldable engagement with said wires and the adjacent end of the condenser to positively prevent displacement of said wires from said binding post, the combination of a pair of elongated levers pivotally connected to each other intermediate their ends and having a first jaw portion engageable with the end of the condenser opposite the said binding post, and having a second jaw portion engageable with the outer end of said spring whereby said spring is depressed upon advancing said jaws relative to each other, said levers having handle portions which extend substantially at right angles to the respective jaw portions so that in use the operator's hand is removed from his line of vision and the work may be observed satisfactorily at all times, said second jaw portion being bifurcated at its extreme outer end whereby it is adapted to straddle the outer end of said binding post, while at the same time depressing said spring, and having an inclined groove therein, beginning at one side thereof and communicating with the notch between opposite sides of said bifurcated end portion, providing a passage between said second jaw portion and the adjacent end of said spring for use in guiding said wires through the hole of said binding post, in the compressed position of said spring.

2. The structure of claim 1, said levers being formed of light gauge, narrow metal strips characterized by their resilience, said handle portions being comparatively long relative to the lengths of said jaw portions, said jaw portions being spaced apart a variable distance, corresponding substantially to the lengths of said condenser and said compression spring together in the compressed and expanded positions, respectively, of said spring, and said handle portions being spaced apart a variable distance, relatively shorter than the spacing between said jaw portions, whereby they abut one another in the compressed position of said spring to thereby limit movement of said jaw portions, upon advancing them relative to each other, whereby crushing of the condenser is positively prevented.
